DOWEL STRUCTURE FOR CONCRETE
ROADWAYS

Louis J. Lind, Pittsburgh, Pa.

Application October 12, 1935, Serial No. 44,714

3 Claims.

(Cl. 94—8)

In the construction of concrete roadways, the same are divided transversely into sections with interposed expansion joints, so that the concrete may expand and contract under changes of temperature; and in modern practice metal bars, termed "dowels" are employed to maintain the sections in proper alignment.

These dowels extend across the joint and have their ends embedded in the concrete of the two sections, one end usually being arranged to bond with the concrete while the material of the other section moves or slides on the bar as the sections expand or contract.

Obviously it is important that these dowels be properly placed and aligned and that they accurately maintain their positions during the casting and setting of the concrete. It is to this purpose that my invention is directed.

In the old art various means were employed for properly positioning the dowels and maintaining them in position, such for instance as cross rods embedded in the concrete of the sections and over which the ends of the dowels were hooked, but this arrangement interferes with the movement of the material of the sections in expanding and contracting, resulting in the stretching and permanent elongation of the dowels which tended to open the joint.

Another method was the support of the ends of the dowels by means of stakes to which the dowels were secured as by clips. This method may be satisfactorily used only when the sub-base of the roadway is suitable for driving stakes and it is difficult and time consuming to properly position and align the individual dowels.

In the use of my invention a plurality of joint structures including the dowels may be set up at the side of the road without interrupting the concrete casting operation, and one by one such structures may be set in place as they are required without interrupting the casting.

In my invention I employ metal chairs which have an intermediate portion upon which the expansion joint member rests and at their ends upwardly extending legs, the legs of the several chairs at either side being permanently connected by cross bars which maintain the chairs in proper positions and relation. The dowels which extend through holes in the expansion joint rest on the cross bars at either side of the joint and are secured as by wires or clips to the cross bars and the legs of the chairs.

The chairs are provided with means for allowing the expansion and contraction at the joint.

55 The expansion joint member, the dowels and

the frame comprising the chairs and cross bars may be set up as a unit at the side of the roadway and put in position when necessary and the concrete cast about the same.

Other novel features of construction and arrangement of parts will appear from the following description.

In the accompanying drawing, wherein I have illustrated a practical embodiment of the principles of my invention, Fig. 1 is a plan view of 10 the joint assembly with the joint member shown in dotted lines.

Fig. 2 is an enlarged section of the joint assembly taken on the line 2—2 in Fig. 1.

Fig. 3 is a broken perspective of the same. 15

Fig. 4 is a view similar to Fig. 2 but with the concrete cast about the assembly.

Referring to the drawing, 1 and 2, in Fig. 4, represent two adjoining sections of concrete roadway between which is interposed the expansion joint member 3 which may be of any suitable material but which is usually formed of asphaltum stiffened with layers of suitable paper or otherwise reinforced.

4 represents the dowels which are preferably steel bars usually of circular cross section and which are positioned transversely of the joint member 3 and extend through properly placed holes in the latter. These holes preferably fit the dowels.

To hold the dowels in proper position and alignment I provide for each dowel a chair preferably made integrally of a metal bar bent up into proper shape and comprising an intermediate base portion 5 having adjacent its center an expansion part 6 which may be formed by offsetting the center of the base 5, as best shown in Figs. 1 and 3, and at each end an upwardly extending leg 7 which rises slightly above the level of the dowels 4. The legs 7 of the chairs at each side of the expansion joint are fixedly connected by the metal cross bars 8 which are welded to the legs or otherwise fixedly secured thereto, thus forming with the chairs a unitary frame which may be fabricated at the factory in proper length to suit the road width in view. The elevation of the cross bars 8 relative to the legs 7 is such that the dowels 4 rest upon the cross bars and against the portions of the legs extending above said cross bars.

The dowels are wired, as at 9, clipped or otherwise secured to the cross bars and legs but in such a manner that in expanding and contracting the chairs and cross bars may move relative to the dowels.

In assembling the joint structure, which may be done prior to putting it in position on the road bed, the joint member 3 is first placed in position in the frame resting on the expansion centers 6 of the chairs, as illustrated in Fig. 1, with the bars 8 parallel therewith. The joint member 3 is usually protected by the sheet metal cover 10 open at its bottom and slipped down over the member 3, the cover 10 having slots 11 extending up from its bottom edges to provide clearance for the dowels 4 when the cover is removed upwardly. The dowels 4 are then inserted endwise through the holes in the member 3 with their ends resting on the frame as shown, and the dowels are 15 then wired to the legs 1 and bars 8.

The assembled joint member is then placed in position in the roadbed and the chairs blocked or otherwise supported, as may be necessary, so that the assembly is properly leveled with the 20 plane of the dowels substantially parallel with the plane in which the finished road surface is to occupy.

Stakes 12 are preferably driven in on either side of the cover 10 to prevent lateral movement 25 of the joint member during the concrete casting operation.

The concrete is now cast embedding the joint assembly and the cover 10 is then lifted off.

It is the usual practice to coat the ends of the 30 dowels at one side of the joint with paraffine or some other substance to prevent bonding with the concrete while the dowels are permitted to bond with the concrete at the other side of the joint. This facilitates the movement of the 35 concrete of the road section relative to the dowels as the concrete expands and contracts.

It is also usual to provide the non-bonding ends of the dowels with slip sleeves 13 whose outer ends are closed and which are only partially telescoped over the ends of the dowels, thereby preventing the dowels from end contact with the concrete when the latter is contracting under low temperatures.

It is evident from the foregoing that the use 45 of my invention greatly facilitates the work of constructing a concrete road, as the joint structures including the joint member, the chairs, cross bars and dowels may be assembled at the side of the road and placed in position as required.

The dowels are properly positioned as the chairs and cross bars may be fabricated as a unitary structure so that the joint member and the dowels will fit into their proper position when 55 installed in the frame. Again, the structure is

such that the dowels and the frame retain their proper positions as the concrete is cast and as the latter sets and hardens.

The chairs and cross bars, being permanently cast in the concrete, reinforce the latter and 5 prolong its life and prevent cracking.

The dowels being properly placed and permanently installed, prevent relative vertical or lateral shifting of the sections and thus insure a permanent road surface. 10

I claim:—

1. A prefabricated frame for supporting the dowels to connect adjacent concrete roadway slabs, comprising a plurality of U-shaped supports, each consisting of an intermediate portion 15 and a leg extending upwardly in a vertical plane from each end of the intermediate portion and parallel to one another, the legs at the corresponding ends of the several supports being disposed in the same planes, and connecting bars rigidly secured to the corresponding legs of each of the supports at either end of the latter and below the upper extremities of said legs to provide seats for the dowels. 20

2. A prefabricated frame for supporting the 25 dowels to connect adjacent concrete roadway slabs, comprising a plurality of U-shaped supports, each consisting of an intermediate portion and a leg extending upwardly in a vertical plane from each end of the intermediate portion and parallel to one another, the legs at the corresponding ends of the several supports being disposed in the same planes, and connecting bars rigidly secured to the corresponding legs of each of the supports at either end of the latter, said 35 bars intersecting the legs below the upper extremities of the latter to form dowel seats.

3. A prefabricated frame for supporting the dowels to connect adjacent concrete roadway slabs, comprising a plurality of U-shaped supports, each consisting of an intermediate portion and a leg extending upwardly from each end of the intermediate portion and connecting bars 40 rigidly secured to the corresponding legs of each of the supports at either end of the latter and 45 at a point below the upper extremities of the legs, the corresponding legs of the several supports being disposed in the same vertical planes and the legs at either end of each support being disposed in a vertical plane at right angles to the 50 first mentioned vertical planes, the dowels being supported in the angles formed by the bars and the opposite legs at each of said supports.
